CLAIM

The ornamental design for a miniature lip plumper, as shown and described.

DESCRIPTION

FIG. 1 is a perspective view of the lip plumper in a closed configuration, from above and to the side.

FIG. 2 is a perspective view of the lip plumper in a closed configuration, from below and to the side.

FIG. 3 is a front side view of the lip plumper shown in FIG. 1.

FIG. 4 is a rear side view of the lip plumper shown in FIG. 1.

FIG. 5 is a right side view of the lip plumper shown in FIG. 1.

FIG. 6 is left side view of the lip plumper of FIG. 1.

FIG. 7 is a top plan view of the lip plumper shown in FIG. 1.

FIG. 8 is a bottom plan view of the lip plumper shown in FIG. 1; and,

FIG. 9 is an exploded perspective view of the lip plumper shown in FIG. 1, showing interior components that are not a part of the ornamental design, for context.

The broken lines shown in the figures represent portions of the miniature lip plumper that form no part of the claimed design. The middle, generally cylindrical component is the mouthpiece of the lip plumper, and is open on both ends, including the obscured end. The upper part is a soft compressible component for creating suction through the mouthpiece. The lowermost part is a cover for the mouthpiece, when not in use.
